H. OSTROVSKY

FROG FOR VIOLIN BOWS

Filed Sept. 22, 1923

Inventor
Harry Ostrovsky
By George A. Prout
atty.

UNITED STATES PATENT OFFICE.

HARRY OSTROVSKY, OF LONDON, ENGLAND.

FROG FOR VIOLIN BOWS.

Application filed September 22, 1923, Serial No. 664,224, and in Great Britain September 22, 1922.

My invention relates to a new method of attachment of the hair to bows for violins, cellos or similar musical instruments, the objects being to impart elasticity to the initial contact of the bow with the instrument and at the same time to improve and to facilitate the attachment or detachment of the hair by an unskilled person.

In musical instrument bows commonly in use, the frog at the butt end is in the form of a solid unyielding block. In the invention described below an elastic form of attachment is provided between the bow stick and the bow hair, this being calculated to improve the tone and technique of the playing.

According to the invention, the frog at the butt end of the bow may be made in either of two alternate forms, differing in their construction but performing the same functions and each achieving the two above objects, namely, elasticity of contact and facility of attachment.

In both forms, the hair is attached to the frog at the butt end of the bow as follows. The frog has on its top side a channel from which extend downward several vertical holes, into any one of which the knot at the end of the hair may be inserted and there held by a removable metal stopper. Alternatively the metal stopper may be in the form of a casing enclosing the ends of the hair and forming a plug which can fit into any one of the holes above mentioned.

In the first form of the frog, to which the following part of the description refers, a metal slide is inserted from the rear into grooves in the sides of the channel, thus covering the hair and holding it in place at its point of insertion into the block. The front end of the slide is of reduced width and is bent upward to form a support for the spring mentioned below.

In order to obtain elasticity of contact between the bow and the instrument, a flat metal L-shaped spring lies along the top side and rear end of the frog and is removably attached to the rear end of the frog by a slot and recessed clamping screw or similar device.

The spring at the top side of the frog lies within the channel mentioned above in which it is free to have a small elastic movement when depressed by contact of the bow with the instrument strings. The spring is supported on its underside by the upward pro-

jection on the slide mentioned above. The effective length of the spring and therefore the amount of deflection may be varied by varying the position of the slide or by using slides having various projections. The front of the spring is formed into a flat D shaped ring embracing the hair. The hair is held and spread against the flat top of this ring by a small plate, which is inserted from the front end and pressed against the hair by turning a small nut running on a screw projecting downward from the plate, or by an equivalent device. In an alternate form, the above mentioned plate is extended forward to form a flexible tongue underlying the hair in such a manner as to give additional support to the hair when pressure is applied to it.

In the second form of the frog, to which the following part of the description refers, the frog at the butt end of the bow consists of two portions. The lower portion runs on a leading screw in the usual manner, while the upper portion is hinged at its top rear corner to a vertical projection from the lower portion.

A projection from the upper portion of the frog lies within a corresponding groove in the lower portion, thus preventing any lateral movement between the two portions.

To obtain elasticity of contact between the bow hair and the instrument strings, a spring is inserted between the hinged and fixed portions of the frog. The method of attachment of the hair to the body of the frog is the same for both forms of the frog and has already been described. The top of the frog is covered by a metal slide formed at its front end into a flat D shaped ring embracing the hair and a portion of the top of the body of the frog. The hair is spread and held against the flat top of the D shaped ring by a plate inserted from the front into the ring below the hair and pressed against it by a clamping screw passing through the lower portion of the ring and through that part of the body of the frog that lies within the ring. In an alternate form the above-mentioned plate is extended forward to form a flexible tongue underlying the hair as previously described.

Projecting downward from the hinged upper portion of the frog is a screw carrying a small nut which, when the hinged upper portion is depressed in playing, strikes against

the fixed lower portion of the frog. The position of the small nut on its screw regulates the amount of depression. The head of the screw lies in a recess in the underside 5 of the lower portion of the frog. The contact of the head of the screw with the top of the recess limits the extent of separation of the two portions of the frog.

The attachment of the hair to the head or 16 point of the bow may be in either of two alternate forms, the object of each of them being to enable the hair to be easily attached to or detached from any existing form of bow head, the devices used being able to accommodate themselves to any of the cavities usual 20 in bow heads.

In one form, the hair is passed through a hole in a small metal plate and is glued in a tube projecting from the plate and having 25 external screw threads on which runs a nut. In the alternate form, the small plate has a key-hole slot into which the hair is inserted, the slot being then closed. The nut runs on an independent screw projecting from the 30 plate. In either form the plate with its attachments is inserted into the cavity in the head of the bow, the nut is then turned, thus wedging the plate in the cavity and spreading and holding the hair.

30 In the accompanying drawing:—

Figure 1 is a side elevation of the frog.

Figure 2 is a mid-section of the frog.

Figure 3 is a plan of the frog.

Figure 4 is an end elevation of the rear end 35 of the frog.

Figure 5 is an end elevation of the front end of the frog.

Figure 6 is a side elevation of the stopper.

Figure 7 is an inverse plan of the stopper.

40 Figure 8 is a plan of the slide.

Figure 9 is a side elevation of the slide.

Figure 10 is a plan of the hair clamp for the frog.

Figure 11 is a front elevation of the clamp 45 at the head of the bow.

Figure 12 is a vertical section on the line 4—4, Figure 11.

Figure 13 is a side elevation of the frog, in a modification.

50 Figure 14 is a vertical section on the line 2—2, Figure 16.

Figure 15 is a plan of the frog.

Figure 16 is an end elevation of the rear end of the frog.

55 Figure 17 is an end elevation of the front end of the frog.

Figure 18 is a vertical section on the line 3—3, Figure 14.

60 Figure 19 is a front elevation of an alternative form of the clamp for the hair in the frog.

Figure 20 is a vertical section on the line 5—5, Figure 19.

65 Figure 21 is a plan of the alternate form of the hair clamp showing the tongue-like projection.

Figure 22 is a vertical section through the same.

Figure 23 is a vertical section through the form of stopper alternate to that shown in Figures 6 and 7.

70 Figure 24 is a horizontal section through the stopper.

Figure 25 is a view in side elevation, partly broken away, showing the device assembled.

75 *a* Figures 1 to 5 is the body of the frog formed of vulcanite or other suitable material, *b* is the groove at the bottom of the body for fitting on to the stick of the bow, and *c* is the nut which attaches the body to the leading screw lying within the stick. Holes *d*, *d* are formed in the body to receive the knot *e* at the butt end of the hair. The top and back of the frog are covered by an L-shaped flat metal spring *f* formed at its front end into a D-shaped ring *g*.

80 The spring *f* has at the lower part of its vertical portion a slot *h* which slips over the threaded portion of the clamping screw *i*, which when tightened holds the spring securely to the body of the frog.

The knot *e* is held in one of the holes *d* by a stopper *j* shown separately in Figures 6 and 7.

85 Alternately the ends of the hair are encased in a tube *w*, Figures 23 and 24, which fits into any one of the holes *d* in the frog.

The hair lying within the channel *k* at the top of the frog is covered by a slide *l* shown separately in Figures 8 and 9.

90 The slide *l* runs in grooves in the sides of the channel and is raised either at its front end or elsewhere to form a support for the flat spring *f*.

95 The hair lying within the D-shaped ring *g* is pressed against the flat top of the ring by a clamping plate *m* shown separately in Figure 10, or by the alternate form shown in Figures 21 and 22.

100 From the plate *m* or its alternate form *v* projects a screw *n* on which runs a small nut *o* which when turned causes the plate *m* to press against the hair.

105 Figures 11 and 12 show the device for holding the hair at the head of the bow. A small metal plate *p* has a hole and carries over the hole an externally screwed tube *q*.

110 A nut *r* runs on the tube *q*. The hair *s* is inserted through the hole in plate *p* and glued inside the tube *q*.

The plate is inserted into the cavity at the head of the bow as shown in Figure 12, and there held by turning the nut *r* which causes the plate *p* to be pressed against the back of the cavity.

115 In the alternative form of the frog shown in Figures 13 to 18, *t* is the lower fixed block and *u* is the upper hinged block.

The lower block has a groove *v* and a screwed nut *w* for attaching the block to the bow stick.

120 A vertical metal plate *x* is screwed to the lower block at *y* and projects upward to the full height of the frog.

The upper block *u* is hinged at its top-rear corner *z* to the vertical plate *x*, a metal block *a* being inserted into the upper vulcanite or like block to form a

hinge with the plate α . A spring b^1 , Figure 14, is inserted in a recess at the back of the upper block u to bear against the vertical plate α for the purpose of keeping the upper block u in its raised position. A projection c^1 on the bottom of the upper block u lies in the corresponding cavity d^1 in the lower block. The top of the upper block u is formed into a channel e^1 from which extend down-
ward three or more holes f^1 . The knot at the butt end of the bow hair is inserted into any one of these holes and there held by a metal stopper j shown separately in Figures 6 and 7. Alternately the ends of the hair are encased in a tube w^1 , Figures 23 and 24, which fits into any one of the holes f^1 in the frog. The channel e^1 at the top of the upper block is covered by a slide k^1 the front end of which is formed into a flat D shaped ring l^1 embracing the hair. A screw m^1 fixes the ring and slide to the upper block. A wedge n^1 is inserted below the hair in order to spread and hold it.

A screw o^1 is passed through a recessed hole p^1 in the lower block t of the frog and is screwed into the upper block u . A flat milled nut q^1 moves on the screw o^1 between the upper and lower blocks. The position of the nut q^1 on the screw o^1 determines the extent to which the upper block may be depressed by pressure on the hair. The contact of the head of the screw o^1 with the top of the recess p^1 limits the extent of separation of the two portions of the frog.

Figures 19 and 20 show a form of the clamp for the hair at the head of the bow alternative to that shown in Figures 11 and 12. A small metal plate r^1 has a keyhole slot s^1 into which the hair is inserted, the slot being then closed to retain the hair. A screw t^1 projects from the plate and carries a nut u^1 . The plate with its attachments is inserted into the cavity at the head of the bow as shown in section in Figure 20 and is there held by turning the nut u^1 which causes the plate r^1 to be pressed against the wall of the cavity. Figures 21 and 22 show the hair clamp with the flexible tongue extension alternate to the form shown in Figure 10. v^1 is the flexible tongue supporting the hair when the latter is pressed.

What I claim and desire to secure by Letters Patent is:—

1. In a bow for musical instruments, including a bow stick and bow hair, the latter having a knot in one end, a connection between the same capable of elastic movement when pressure is applied to said hair in playing, said connection comprising a frog having a body portion, means for securing said

frog to said bow stick, a channel opening in the top of said body, said body being apertured to receive said knot in one end of said bow hair, means for securing said knot in said aperture, a spring member for facilitating said elastic movement, a cover of resilient material for said channel and aperture in the body, and means for securing said hair at the head end of the bow stick.

2. In a bow for musical instruments, including a bow stick and bow hair, a connection between the same capable of elastic movement when pressure is applied to said hair in playing, said hair having a knot in one end, said connection comprising a frog having a body portion, means in said body portion for securing said frog to the stick, a channel opening in the top of said body, a plurality of apertures in said body to receive the knot in said bow hair, a stopper for securing the knot in one of said apertures, a plate at one end of said frog for spreading said hair, a cover of resilient material for said channel and apertures, and the hair lying therein, and means for securing said hair at the head end of the bow stick.

3. A bow for musical instruments as claimed in claim 2, means for securing the bow hair to the head of the bow consisting in a cavity in the head of said bow, an apertured plate member, an outwardly threaded tube secured to said plate, a nut to engage and rotate on said threaded tube, said device being capable of being inserted in said cavity, whereby said hair after being inserted through the aperture in said plate, is held in place by rotating said nut on said tube, forcing the plate against the wall of said cavity.

4. A bow for musical instruments including a bow stick and bow hair, a frog comprising a body portion, means for securing said frog to said bow stick, a grooved channel opening in the top of said body, apertures in said body to receive a knot in the butt end of said bow hair, means for securing said knot in one of said apertures, a slide capable of being inserted along said grooves in the channel opening for covering and holding down the hair lying therein, a spring cover member for covering the top and back of said frog and terminating at one end in a hair spreading member consisting of a plate extending laterally of said bow, and a screw for causing the same to be raised and lowered, and means for securing the hair at the head of said bow.

In testimony whereof I affix my signature.
HARRY OSTROVSKY.
